SINGLE RUNNER SLED

Edgar L. Kaup, 643 Panama Drive, Littleton, Colo.

Filed Feb. 1, 1965, Ser. No. 33,640

Term of patent 3½ years

(Cl. D34—15)

FIG. 1.

FIG. 2.

FIG. 3.

FIG. 3 is a front elevational view partly in cross-section along line 3—3 of FIG. 2.

The left-side elevation is a mirror-image of the right-side elevation and the bottom is plain.

I claim:

The ornamental design for a single runner sled, as shown and described.
